UNITED STATES PATENT OFFICE.

LOUIS DREIFUSS, OF NEW YORK, N. Y.

DESIGN FOR A LACE MEDALLION.

52,912.

Specification for Design.

Patented Jan. 28, 1919.

Application filed November 19, 1918. Serial No. 263,220. Term of patent 3½ years.

To all whom it may concern:

Be it known that I, LOUIS DREIFUSS, a citizen of the United States, and a resident of the city of New York, borough of Manhattan, in the county and State of New York, have invented a new, original, and ornamental Design for a Lace Medallion, of which the following is a specification, refer-

ence being had to the accompanying drawing, forming part thereof.

The figure is a face view of a lace medallion showing my new design.

I claim:

The ornamental design for a lace medallion as shown.

LOUIS DREIFUSS.
